(57) **CLAIM**

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof;

FIG. 7 is an opposite side front perspective view thereof;

FIG. 8 is a front perspective view of a shoe showing my new design in an alternative embodiment;

FIG. 9 is a side view thereof;

FIG. 10 is a rear perspective view thereof;

FIG. 11 is a rear view thereof;

FIG. 12 is an opposite side rear perspective view thereof;

FIG. 13 is an opposite side view thereof; and,

FIG. 14 is an opposite side front perspective view thereof.

The even-length broken lines in FIGS. 1-7 represent stitching that forms no part of the claimed design. The uneven-length broken lines immediately adjacent to the shaded area define the bounds of the claimed design and form no part thereof. The uneven-length broken lines depicting the remainder of the shoe form no part of the claimed design.

1 Claim, 14 Drawing Sheets
